Patented July 27, 1965

201,754

COMBINATION CAN OPENER AND KNIFE SHARPENER

John E. Reed, Glen Ellyn, Ill., assignor to Sunbeam Corporation, Chicago, Ill., a corporation of Illinois

Filed Jan. 7, 1965, Ser. No. 83,320

Term of patent 14 years

(Cl. D37—1)

Fig. 1.

Fig. 2.

Fig. 3.

FIG. 1 is a perspective view of a combination can opener and knife sharpener embodying my design;

FIG. 2 is an enlarged front view thereof;

FIG. 3 is a top view thereof;

FIG. 4 is a side view thereof; and

FIG. 5 is a rear view thereof.

I claim:

The ornamental design for a combination can opener and knife sharpener, as shown.
